MODULATED CARRIER WAVE TRANSMITTER

Newsome Henry Clough and Ernest Green,
Essex, England, assignors to Radio Corpora-
tion of America, a corporation of Delaware

Application October 9, 1937, Serial No. 168,167
In Great Britain November 19, 1936

1 Claim. (Cl. 179—171.5)

The present invention relates to modulated carrier wave transmitters, particularly of the floating carrier type.

It is usual in floating carrier type transmitters in which the carrier power is a function of the rectified modulation envelope, to amplify the modulating potentials, which may be taken from any pair of points in the cascade speech amplifier to rectify the amplified potentials and 5 to pass the resultant direct current after smoothing or filtering amplification, through a resistance in series with a bias source in a control circuit of the main modulation stage. The voltages across the resistance and source are opposed, 10 and thus the total bias of the main modulator, varies with the rectified modulation envelope. Such an arrangement is shown in United States Patent Number 2,114,336, dated April 19, 1938.

Usually the modulation power is converted to 20 two-phase by means of an iron cored transformer and is rectified by means of a full wave rectifier. In order to maintain a rectilinear performance for varying power and frequency such a system has to be so operated that the maximum current passed through the iron cored transformer 25 produces only a comparatively weak flux in the core. Thus, rectification is effected at low power and the rectified output has to be amplified.

Such a method has the disadvantage that it 30 is expensive on account of the tube amplifiers, and that it is difficult to arrange the direct current amplifier so that its output can be applied to two points, both of which float with respect to ground where the modulation frequency stage 35 is in the high potential end of the series circuit, or to a point in the high tension supply source in the modulator stage grid network.

The accompanying Figure 1 shows, in simplified diagrammatic form one arrangement of the 40 nature referred to. The circuit of Figure 1 is, per se, known the invention being concerned with the means for applying floating carrier control potential at the terminals T₃, T₄. In the system of Figure 1 the modulating stage represented 45 by a tube V₁ is in series with a modulated stage, which is, of course, a tube or bank of tubes but is represented merely by a resistance R₁, the said stage V₁ being connected to the positive side of its associated modulated stage R₁ and floating 50 bias for floating carrier action being applied at terminals T₃, T₄, across a resistance R₂ in series with a fixed bias, comprising a direct current source B and a speech input impedance, not shown, connected at T₁, T₂ between the filament 55 and grid of the modulating stage. The floating

bias is generally obtained from rectified speech and applied in a sense to oppose the direct current source B, through a direct current amplifier (not shown) having its output terminals connected at T₃ and T₄. Neither of the points 5 T₃ and T₄ is at ground potential for the filament itself must float in order that the carrier amplitude may change. Therefore the whole of the direct current amplifier including its anode, filament, and bias circuits must be arranged to 10 float with respect to ground.

The present invention aims at overcoming these difficulties by eliminating the iron cored transformer and effecting rectification at high power, preferably, though not necessarily, by means of 15 a thermionic device operating as an anode bend rectifier. Arrangements may also be made for providing different operation and release times, the usual requirement being a quick operating and a slow release time. 20

In general, the fixed bias of the modulating stage is such that in the quiescent condition, i. e., in the absence of modulation, the carrier is at a previously selected value and the anode bend rectifier is so biased that its anode current is zero or is well down the bend. 25

The circuits are so arranged that when modulation potentials are applied to the rectifier, the rectifier becomes conductive on each positive half cycle and the resultant increase of rectifier current increases the carrier level. Preferably a condenser is connected into the rectifier circuit and is preferably so arranged that its charge changes quickly during rectification and slowly in the continued absence of rectification, i. e., 30 35 of modulation.

The invention illustrated in the attached drawings wherein Figure 2 shows a high power rectifier of the anode bend type arranged in accordance with the present invention. Figure 3 illustrates an embodiment of a modulating system of floating carrier type arranged in accordance with my invention. Figure 4 is in effect a combination of Figures 2 and 3. Figures 5, 6 and 7 are modifications of the arrangement of Figure 4, while 40 45 Figure 2a illustrates a form of the high frequency unit R₁ of the prior modifications.

In the arrangement of rectifier circuit shown in Figure 2 the rectifier is constituted by a tube V₂ which has its anode connected to a suitable 50 source B₁ of positive potential through a resistance R₃ and its cathode to one end of a potential source B₂, modulation potentials being applied at terminals T₅, T₆. Between anode and cathode of tube V₂ is connected a condenser C shunted 55

by a resistance R_2 . When the rectifier tube V_2 is not conducting the condenser C is charged. When modulation potentials are applied to the grid of tube V_2 , the tube conducts on successive positive half cycles and the condenser charge is thus reduced at a rate which can be made rapid by suitable selection of the tube. When modulation potentials cease to be applied to the grid of the rectifier tube V_2 , the condenser again recharges at a rate which can be made slow. The greater the value of the resistance R_3 or the value of the condenser C the slower will be the recharge rate.

The output from the rectifier V_2 may be applied across a resistance connected in series with a suitable biasing potential in the grid filament input circuit of the modulating stage, i. e., R_2 of Figure 2 may be the same resistance as R_2 of Figure 1. The modulated stage indicated diagrammatically at R_1 in Figure 1 may be as indicated at R_1 in Figure 2. This circuit per se has been disclosed in prior patents such as Ditcham United States Patent #2,118,172, dated May 24, 1938, and comprises an additional tube V_4 with an output circuit 10 and an exciting circuit 12 the tube's output impedance being as shown in series with the output impedance of V_1 and being supplied by direct current from the same source. In other words R_1 of Figure 2 may replace R_1 of Figures 1, 3 and 4 by substitution at points *a* and *b* of said circuits.

In the modulator system of Figure 3 where, as in Figure 1 the modulating stage V_1 is in series with the modulated stage R_1 there is provided an input tube V'_1 the anode of which is connected to a source of positive potentials (not shown) through a resistance R_4 and to the grid of the modulating stage V_1 , the cathode being connected to the low potential side of the modulated stage 40 through a source of potential B_1 . Modulation input is applied at T_1 , T_2 in the grid-cathode circuit of tube V'_1 the output from the rectifier (not shown in Figure 3) being applied at T_3 , T_4 , across a resistance R_2 connected in series with the grid biasing source B of the input tube V'_1 . It should be noted that in this arrangement the input tube V'_1 requires an increase in negative bias on modulation, to thereby render tube V'_1 less conductive in order to decrease the negative bias on V_1 and to increase the amount of carrier applied to the output by V_1 . That is the change of voltage developed across R_2 when modulation occurs must be in a sense to add to the source B and increase the total negative bias on tube V'_1 , whereas in Figure 1 in which tube V_1 in the absence of signals is biased more negatively the bias applied at T_3 , T_4 by the rectifier should be such as to oppose the constant source B and decrease the total negative bias on tube V_1 . Incidentally it may be noted that with the input tube arrangement the input tube V'_1 may be arranged to have zero bias or even positive bias in the quiescent condition.

The method of the invention may be applied in a variety of ways. Thus in the arrangement of Figure 4, which is in effect a combination of Figures 2 and 3, V_2 is an anode bend rectifier tube having its anode connected through a resistance R_3 to the positive side of a source (not shown) of potential. Modulation potentials for rectification are applied at T_5 , T_6 in the grid filament circuit which also includes a suitable bias source B_2 and a grid resistance R_5 shunted by a condenser C_3 . Between the anode and filament of V_2 are connected in parallel a re-

sistance R_6 and a condenser C_1 . Series connected modulating and modulated stages V_1 , R_4 are provided, the modulating stage V_1 being on the positive side of the modulated stage R_1 and associated with these stages is an input tube V'_1 having its anode connected to a source (not shown) of positive potential through a resistance R_4 . The filament of V'_1 is connected through a source B_1 of negative potential to ground, to which, also, the negative side of the modulated stage R_1 is connected. This source may, in practice, be combined conveniently with the above mentioned source (not shown) which supplies the anode of the rectifier V_2 . The filament of the input tube V'_1 is also connected to the filament of the rectifier and thus also to the other end of the resistance and condenser combination R_2 , C_1 associated therewith. The grid of the input tube V'_1 is connected through a resistance R'_5 and a source B of grid bias to the anode of the rectifier V_2 and thus also to one end of the resistance and condenser combination R_2 , C_1 associated with the said rectifier. Modulation potentials for modulation purposes are applied at T_1 , T_2 , between the grid and filament of the input tube the lead to the grid including a blocking condenser C_2 . On the application of modulation potentials at T_5 , T_6 the rectifier tube V_2 conducts on positive half cycles thus shunting the resistance R_2 associated therewith. The rectifier anode potential thus falls and this decrease in potential supplements the potential in B and consequently the resultant negative grid bias of the input tube V'_1 increases to make the potential of the grid of V_2 less negative and causes an increase of carrier levels in R_1 as before. The condenser C_1 smooths out changes and introduces a delay in the reduction of carrier level so that the latter does not die down quickly between periods of heavy modulation. The resistance R_6 serves to bias back the rectifier tube (by virtue of a direct current drop of potential caused by grid current) against overdriving. Thus a limit is put to the level to which the carrier can rise.

The arrangement of Figure 4 may be modified as indicated in Figure 5, which shows part of the modified circuit. Here instead of providing a separate battery B_2 , as the source for biasing the rectifier V_2 , bias is obtained from a point TP on the source B , this point being connected through a resistance RTP and resistance R_5 in series to the grid of tube V_2 .

In a further modification partly shown in Figure 6 of the arrangement of Figure 4 the rectifier V_2 has its anode connected directly to the positive side of the source of potential and its filament connected to ground and to the terminal T_6 through a source of bias potential B_2 . A resistance R_2 and shunt condenser C_1 associated with the rectifier, instead of being connected between the anode and cathode of the rectifier are connected at one end to the cathode and at the other end are connected through a potential source B and resistance R_5' to the grid of the input tube V'_1 (not shown). In this arrangement modulating potentials cause the condenser C_1 to charge from the source of potential connected between the anode and filament of the rectifier. Slow discharge takes place through the resistance R_2 which is of high value.

The arrangement of Figure 6 may be modified by dispensing with the source of biasing potential B and correspondingly increasing the potential

of the source connected between the anode and filament of the rectifier for, in Figure 6 these two sources are effectively in series. The cathode end of the resistance R_2 may then be taken to a 5 tapping on the biasing source B_2 of the rectifier, or the said end of the said resistance may be taken to a point on the source connected between anode and filament of the rectifier (e. g., by means of a tap on a potentiometer connected 10 thereacross). In a further modification shown in Figure 7 separate bias to the rectifier is dispensed with by using a second tap on the potentiometer just mentioned. In Figure 7 the potentiometer is marked PR and the two taps 15 PR_1 and PR_2 , the former being connected through the resistance R_2 .

The filaments of the several tubes may be heated in any suitable manner, and, of course, indirectly heated cathodes may be used. The 20 course of potential may be batteries or rectifier fed resistances with potentiometer taps or other suitable sources.

The invention, though primarily intended for the purposes hereinbefore described, is not exclusively limited to such use; for example the 25 circuits of the invention may be employed for "keying" a telegraph transmitter by audio frequency line signals, in which case the "operating" and "release" times would be made equal.

30 We claim:

In a modulation system of the type wherein high frequency wave energy to be modulated flows in a stage connected in a series including the output electrodes of an electron discharge 35 modulator tube and a source of direct current potential with means for applying modulating potentials to a control grid of the modulator

tube to control its impedance and thereby control the amplitude of the high frequency currents supplied by said high frequency stage and means for additionally controlling the impedance of said modulator tube in accordance with the envelope 5 of the modulating potentials to thereby control the amplitude of the high frequency current comprising, a second discharge device having an anode, a cathode, and a control grid, means connecting the anode of said second tube 10 substantially directly to the grid of said modulator tube, a connection between the cathode of said second tube and a point on said series circuit a source of potential connected with the control grid and cathode of said second discharge 15 device said source of potential normally biasing the control grid of said device negatively relative to the cathode of said device by a potential such that it passes current and thereby maintains the control grid of said modulating tube 20 negative and means for increasing the negative bias on said control grid of said second electron discharge device as the mean amplitude of the modulating potentials increases to thereby reduce the negative potential on the control grid 25 of said modulator tube comprising an impedance and a condenser in parallel in the input circuit of said second discharge device, a rectifier tube having an anode, a cathode and control grid, means connecting the anode and cathode of said 30 rectifier tube to spaced points on said impedance, and means for applying modulating potentials to the control grid and cathode of said rectifier tube.
